WILLARD T. MUNSON, OF SCRANTON, PENNSYLVANIA, ASSIGNOR TO COLLINS SUPPLY
AND EQUIPMENT COMPANY, OF SCRANTON, PENNSYLVANIA

OIL GUARD FOR SPINNING RINGS

Application filed August 11, 1932. Serial No. 628,433.

This invention relates to spinning rings and their holders and has special reference to an oil splash guard for such rings and holders.

5 One of the problems which silk mill owners have had to meet has been to protect the silk in spinning machines from splashing of the oil onto the silk from the traveller as it picks up the lubricant which is applied to 10 the ring. Various devices have been tried out to provide protection for the bobbins from this oil but none of these devices hitherto used have proven satisfactory since most of them require either to be fixed permanently to the ring rail or to be secured by the 15 screws which hold the ring holder in position so that they cannot readily be removed for cleansing.

One important object of the invention is to 20 provide an improved oil guard for this purpose adapted to be readily attached to a ring holder having upstanding flange portions to support the ring.

A second important object of the invention 25 is to provide an improved arrangement of this kind wherein the guard is held in position on the ring holder by the ring itself.

A third important object of the invention 30 is to provide an improved oil guard for this purpose wherein the guard is mounted in such manner that lifting the ring from its holder permits free lifting of the guard from the holder.

A fourth important object of the invention 35 is to provide an improved form of oil guard especially adapted for use in connection with the ring and holder disclosed in the patent to B. L. Bloom, No. 1,663,620.

With the above and other objects in view 40 as will be hereinafter apparent, the invention consists in general of certain novel details of construction and combinations of parts hereinafter fully described, illustrated in the accompanying drawing and specifically 45 claimed.

In the accompanying drawing like characters of reference indicate like parts in the several views, and:

50 Figure 1 is a plan view of the holder, ring and oil guard assembled.

Figure 2 is a section on the line 2—2 of Figure 1.

Figure 3 is an enlarged detail section on the line 3—3 of Figure 1.

Figure 4 is a detail section on the line 4—4 of Figure 1 but with the ring removed.

The holder 10 comprises a flat annular plate or ring of sheet metal having an upstanding annular flange 11 at its inner periphery to assist in guiding the usual traveller (not shown). The holder 10 has spaced around its outer periphery upstanding portions 12, preferably three in number. The lower central part of each upstanding portion is cut with an inverted U-shaped slit to 65 form a lug 13 which is pressed inwardly to extend upwardly on the inner side of the respective portion 12 and thus form a ring seat as can be clearly seen in Figure 3.

The ring itself has the usual annular body 70 dished inwardly and provided with a depending bead 15 at its inner periphery beneath which the feet of the traveller engage, this bead being spaced from the flange 11 when the parts are assembled. A vertical flange 16 depends from the outer periphery of the ring body 14 and rests on top of the lugs 13, fitting tightly between the upstanding flange portions 12 so that the ring is held securely in place by this frictional 75 engagement with its holder but may be readily lifted out of the holder without the use of tools.

The oil guard consists of an upstanding arcuate strip 17 of thin sheet metal extending around the outer periphery of the ring and holder somewhat more than 180 degrees. This guard rests at its lower part against the outer faces of certain of the flange portions 12 and opposite each of the portions 90 12 against which it rests is slotted and bent to provide a spaced pair of inwardly offset lugs 18 of slightly less height than the lug 13 and so spaced that the lug 13 fits between them. 95

By reason of this construction, the guard may have its lug provided portions slipped over the portions 12 of the holder and then, by placing the ring in the holder, the guard is secured in position. Obviously, the 100

guard may be removed for cleansing by lifting out the ring and then lifting the guard up. It is to be noted that each pair of lugs 18 and the adjacent part of the body 5 of the guard form a species of sleeves so that the guard may be said to be provided with sleeves at its lower edge fitting over the upstanding flange portions of the holder.

It will be further noted that the guard 10 closely embraces the sides and rear of the space in which the traveller moves and, the bobbins being located behind the rings, splashing of oil from the traveller onto the bobbin is absolutely prevented.

15 There has thus been provided a simple and efficient device of the kind described and for the purpose specified.

It is obvious that minor changes may be made in the form and construction of the 20 invention without departing from the material spirit thereof. It is not, therefore, desired to confine the invention to the exact form herein shown and described, but it is desired to include all such as properly come 25 within the scope claimed.

Having thus described the invention, what is claimed as new, is:

1. The combination with a spinning ring holder having upstanding spaced peripheral 30 flange portions; of an oil guard consisting of an arcuate strip of metal extending around the outer periphery of the holder and provided with spaced sleeves at its lower edge fitting removably on the spaced flange portions 35 of the holder.

2. The combination with a spinning ring holder having upstanding spaced peripheral flange portions; of an oil guard consisting 40 of an arcuate strip of metal extending around the outer periphery of the holder and provided with spaced sleeves at its lower edge fitting removably on the spaced flange portions of the holder, and a ring fitting between the flange portions of the holder over the 45 upper ends of the sleeves to retain the guard in place.

3. The combination with a spinning ring holder having upstanding spaced flange portions on its outer periphery, said flange portions 50 being each provided with a centrally disposed inset lug forming a ring rest; of an oil guard consisting of an arcuate strip of metal extending around the outer periphery of the holder and resting against the outer faces of the flange portions, said guard being provided on its inner face with spaced pairs of lugs arranged to engage over the side edges of said flange portions and spaced to embrace the lugs of said flange portions 55 between them.

4. The combination with a spinning ring holder having upstanding spaced flange portions on its outer periphery, said flange portions 60 being each provided with a centrally disposed inset lug forming a ring rest; of

an oil guard consisting of an arcuate strip of metal extending around the outer periphery of the holder and resting against the outer faces of the flange portions, said guard being provided on its inner face with spaced pairs of lugs arranged to engage over the side edges of said flange portions and spaced to embrace the lugs of said flange portions between them, said guard lugs being of slightly less height than the lugs of the flange portions, and a ring embraced by said flange portions and resting on the lugs thereof over the guard lugs to hold the guard from displacement.

80 In testimony whereof I affix my signature.

WILLARD T. MUNSON.
